United States Patent Office

Des. 215,431
Patented Sept. 30, 1969

215,431

VIAL RACK

Ernest L. Allen, 82 Main St.,
Nashua, N.H. 03060

Filed Jan. 14, 1969, Ser. No. 15,343

Term of patent 14 years

Int. Cl. D24—02; D6—01

U.S. Cl. D16—1

FIG. 1

FIG. 4

FIG. 2

FIG. 1 is a front view of the vial rack, showing my new design;

FIG. 2 is a rear view thereof;

FIG. 3 is a side view thereof; and

FIG. 4 is a top plan view thereof.

The broken lines are shown for illustrative purposes only.

I claim:

The ornamental design for a vial rack, as shown and described.
